F. J. STRAUB

PALLET FOR BLOCK MAKING MACHINES

Filed May 27, 1924

Patented Mar. 16, 1926.

1,577,383

UNITED STATES PATENT OFFICE.

FRANCIS J. STEAUB, OF NEW KENSINGTON, PENNSYLVANIA.

PALLET FOR BLOCK-MAKING MACHINES.

Application filed May 27, 1924. Serial No. 716,172.

To all whom it may concern:

Be it known that I, FRANCIS J. STRAUB, a citizen of the United States, residing at New Kensington, in the county of Westmoreland and State of Pennsylvania, have invented certain new and useful Improvements in Pallets for Block-Making Machines, of which the following is a specification.

My invention relates to the manufacture 10 of building or other blocks, and particularly to an improvement in pallets used in connection with the pressing and transporting of the blocks.

In this art, it is customary to form the 15 block of any suitable mixture, as concrete, clay, cinder, etc., within a suitably shaped mold by pressure, either with or without a core, and to support the block upon a bottom plate or pallet which is utilized as a 20 support for transporting it to any suitable point for drying or further handling.

The present invention has in view to provide a pallet having a continuously plane 25 upper surface interrupted between its outer and inner portions by an upwardly projecting uninterrupted rib adapted to form a corresponding groove on the under face of the block. Such rib greatly increases the stability of the pallet to prevent it from bending 30 under the weight of the block when carried, and permits the use of comparatively thin sheet metal, thereby greatly reducing its weight.

Ordinarily, pallets for molding blocks 35 have been made of continuously flat cast metal, but these are objectionable on account of their weight, and involve considerable additional labor in the work of carrying away large numbers of molded blocks each 40 provided with its supporting heavy cast iron pallet. On the other hand, if cast iron pallets are made sufficiently thin for lightness, they frequently break under the load or in handling, and are a constant source of expense.

My invention is designed to overcome 45 these various objections, and also to provide means for forming an uninterrupted continuous rectangular groove upon the under 50 face of the molded block and adapting it to more efficient usefulness when set in place, in the manner more specifically hereinafter described.

A further object is to provide, in a pallet 55 of such construction, a plurality of centrally arranged elongated core openings through

the continuously flat area within the surrounding rib, whereby corresponding transverse cores or holes may be made in the finished block in the operation of molding.

More specifically stated, the present form of pallet is especially designed for use in connection with the manufacture of extra wide foundation blocks, having elongated core openings adapted to register with the 60 core openings of superimposed blocks.

The present invention is somewhat similar to that of my prior Patent No. 1,486,056, issued March 4, 1924.

In the drawings, showing one preferred 70 embodiment of the invention:

Fig. 1 is a plan view of the pallet;

Fig. 2 is a side edge view;

Fig. 3 is a sectional view, showing an ordinary wall block laid on a foundation 75 block;

Fig. 4 is a view in cross section, showing the pallet in supporting position under the block;

Fig. 5 is a perspective view of one of my 80 improved pallets, detached.

Referring to the drawings, the simplest form of pallet illustrated in Fig. 1 is a rectangular piece of comparatively thin sheet metal 2, provided throughout a portion of 85 its length and width with a continuous pressed-up ridge 3 conforming to the rectangular outline of the plate, adapted to form the resulting groove 4 in the molded block A. Said block, as shown in Figs. 3 90 and 4, is supported upon the pallet 2 within the cavity of a suitable mold and provided with the usual plunger bottom, upwardly above which the pallet is supported in the usual way. The formation of the mold for 95 whatever material is used, is one familiar to those skilled in the art, and need not be described.

When the block has been sufficiently pressed and molded to shape, and removed 100 from the mold, it may be lifted by the workmen grasping each end of the supporting pallet and carried away to any drying position, as is ordinarily done. The presence of the rib 3 extending upwardly 105 through the middle portion of the pallet greatly stiffens it against buckling, enabling the use of a comparatively thin section of sheet metal, as steel, and the resulting block is provided on its under side with the continuous rectangular groove, rounded at the corners, as shown.

For the purpose of providing molded openings 5 at intervals through the block A, the pallet is perforated with a series of similar holes 6, transversely elongated, rounded at the ends, or of other shape, centrally of the plate and surrounded by continuous ridge 3, as shown. The pallet as thus made is of standard length, as sixteen inches, and approximately one and one-half the usual standard width, or twelve inches, and especially adapted to the making of extra wide blocks of standard length for foundations.

By reason of the elongated openings 6, the formed block is provided with the corresponding openings 5, which correspond lengthwise and partly register with the usual openings 7 of the standard wall blocks 8, of eight inch width. The foundation blocks A, of twelve inch width, extend beyond underneath the upper wall block layer at one or both sides, as desired, and for one or more layers below.

The pallet 2 is cut out at each end, as at 9, for clearance of co-acting vertical inwardly extending portions of the mold and also providing ample grasping clearance for the fingers of the workman in lifting or carrying the block.

The presence of the deep longitudinal and transverse grooves running along within the ends and sides of the bottom of the block, when laid with a suitable binder on the opposite flat face of an adjacent block or surface also ensures a strong rigid anchoring connection, as will be obvious.

The pallet is easily, quickly, and cheaply made by stamping from sheet metal, with a

minimum of waste, and is maintained in a flat condition under the load of the block by reason of the squared rib, surrounding the central smooth area, within the side and end edge portions. It may be compactly stacked with other similar pallets, and will maintain its shape and efficiency indefinitely.

The construction and manner of operation of the invention will be readily understood and appreciated from the foregoing description. It greatly simplifies and cheapens the ordinary pallet, while increasing its efficiency and reducing the weight. The resulting advantage of the grooved block greatly adds to the stability of the wall or other structure in which it is used, and the invention materially contributes to the efficiency of the workmen in molding the blocks, while reducing their labor as to the aggregate weight to be carried throughout an entire day's work.

What I claim is:

A molding pallet made of comparatively thin sheet metal and provided with a continuous upwardly extending groove-forming rib extending longitudinally and transversely across its surface intermediate the middle smooth surface and the outer edge portions, and having a pair of transverse core openings through the middle portion of the pallet within the surrounding rib, and concave clearance openings cut in each end of the pallet.

In testimony whereof I hereunto affix my signature.

FRANCIS J. STRAUB.
